18 Claims. (Cl. 29—157)

This invention relates to hollow articles and more particularly to the forming of tubes in heat exchangers.

In the formation of hollow articles, such as heat exchangers, it has been found that there are certain advantages to fabricate the article from a plurality of metal component sheets joined together by selectively welding their adjacent areas in a pattern defining a system of desired passageways wherein the system of passageways are defined between unjoined portions of adjacent sheets and laterally defined by welded portions of adjacent sheets. This resultant structure, containing the system of passageways, can be obtained by a process such as that disclosed in the patent to Grenell, U.S. No. 2,690,002, granted on September 28, 1954.

In the process of the aforesaid patent, a pattern of weld-inhibiting material is applied to a clean surface of a sheet of metal. A clean surface of a second sheet of metal is superimposed on this surface and the two sheets are secured together to prevent relative movement between them and then pressure welded together, as by hot rolling, in the adjacent areas thereof which are not separated by the weld-inhibiting material. The welding of the sheets results in a substantial elimination of any interface between the superimposed sheets except in the areas defined by the weld-inhibiting material so as to provide a substantially seamless or solid integral sheet. Subsequent to the welding operation, the resultant blank or sheet is usually softened as by annealing to make it more pliable, and if desired, cold rolled and again softened by annealing. As noted above, the weld-inhibiting material results in an unjoined portion between the outer faces or surfaces of the sheet metal blank. After softening the blank, the unjoined portion is expanded by injecting therein a fluid pressure of sufficient magnitude to permanently distend in the area of the unjoined portion to form the desired pattern of passageways. As disclosed in the aforesaid patent, the distention may be done in varied manners so that the expanded system of passageways will bulge either out of one or out of both faces of the sheet metal blank.

For some applications, as in U.S. Patent 2,740,188, granted April 3, 1956, it is sometimes desirable to distend at least a portion of the unjoined areas in the sheet metal blank by mechanical means such as a mandrel. In other applications, it is often desirable, irrespective of the manner in which the sheet metal blank is distended, to further size the distended passages to obtain the configuration and dimensions required. Generally with such mechanical distensions or sizing operations no difficulty is encountered when the sheet metal blank is fabricated of metals having the same physical characteristics. However, in sheet metal blanks formed of component metal sheets, such as a hard and a soft sheet, due to a difference in their physical properties, such as in the elastic limits of the metals, heretofore conventional methods and tools for mechanical distention have proven inadequate. Such conventional tools force the softer metal of the blank to become distended to a greater tube height than the harder metal whereby the softer metal is bulged out of the faces of the blank a greater amount than the harder metal. Due to these disadvantages, it has been difficult or impossible to control the

2

distention of the tubular passageways so as to obtain precision in the configurations desired.

Accordingly it is an object of this invention to provide a novel tool and process eliminating disadvantages of the prior art.

Another object of this invention is to provide a novel tool and process for mechanically distending tubular passageways contained in a metal tube sheet formed from complementary sheets of diverse metals.

10 Another object of this invention is to provide a novel tool and process for mechanically sizing a tubular passageway contained in a metal sheet formed from complementary metal portions having different physical characteristics.

A further object of this invention is to provide a novel tool and process for controlling the mechanical distention of a tubular passageway contained in a metal tube sheet formed from complementary metal portions having different physical characteristics.

A still further object of this invention is to provide a novel tool and process for the mechanical sizing of a tubular passageway contained in a metal tube sheet formed from metal complementary portions having different elastic limits.

Other objects and advantages will become more apparent from the following description and drawings in which:

FIGURE 1 is a side elevational view of a tool illustrating an embodiment of this invention together with a perspective view of a portion of a distendable panel shown partly in cross-section;

FIGURE 2 is a sectional view taken along lines II—II in FIGURE 1;

FIGURE 3 is a cross-sectional view taken along lines III—III in FIGURE 1;

FIGURE 4 is a sectional view taken along lines IV—IV in FIGURE 1;

FIGURE 5 is a perspective view of the tool or mandrel illustrated in FIGURE 1 shown entering a distendable panel;

FIGURE 6 is a side elevational view of a tool illustrating another embodiment of this invention in conjunction with a perspective view of a portion of another distendable panel partly in cross-section;

FIGURE 7 is a side elevational view in section of the tool or mandrel of FIGURE 6 shown within the distendable panel of FIGURE 6;

FIGURE 8 is a cross-sectional view taken along lines VII—VII in FIGURE 7;

FIGURE 9 is a sectional view taken along lines IX—IX in FIGURE 7;

FIGURE 10 is a perspective view of a portion of the inflatable panel in FIGURE 6 subsequent to mechanical distensions.

55 FIGURE 11 is a side elevational view of a type of tubular conduit in a distendable panel for illustrating another embodiment of this invention;

FIGURE 12 is a side elevational view in section showing the distention of the panel of FIGURE 11 in accordance with another embodiment of this invention; and

60 FIGURE 13 is a perspective view of a portion of the inflatable panel of FIGURES 11 and 12 subsequent to mechanical distention.

In accordance with this invention it has been discovered that in panels or tube sheets formed of a softer component sheet superimposed upon a harder component sheet, wherein the difference in hardness may result from the difference in elastic limits of the components, in which the adjacent areas of the component sheets are selectively welded together in a pattern defining a desired system of passageways, controlled distention of the passageways can be obtained by regulating the distending force on

the softer metal relative the force of distention applied on the harder metal by means of a tool and a novel method of distention. The controlled amount of distending forces on the respective component sheets is obtained in accordance with this invention by a mechanical punch or mandrel having correlated configurations provided in its working portions for the distention of the component sheets in the expansion or sizing of the passageways contained in the blank. The working portions of the tool of this invention are provided with oppositely disposed bearing surfaces for application of the distending forces against the harder sheet and against the softer sheet. The working portion of the mandrel will have its cross-sectional configuration dimensions corresponding to the cross-sectional configuration desired to be imparted in the distended tubular passageway. And, the amount of distention desired in each sheet is obtained by controlling the amount of area of the bearing surface pressing against the softer metal relative to the amount of area of the bearing surface pressing against the harder metal component sheet. To obtain such controlled distention the ratio of the area of the bearing surface pressing against the softer sheet to the area of the bearing surface pressing against the harder sheet is regulated to equal the ratio of the elastic limit of the harder sheet to the elastic limit of the softer sheet multiplied by the ratio of the amount of distention desired in the softer sheet to the amount of distention desired in the harder sheet, and further multiplied by the ratio of the thickness of the softer sheet to the thickness of the harder sheet.

As will be understood the specific numerical areas of each bearing surface will necessarily be dependent either on personal preferences, or on the specific dimensions of the tubular passageway to be distended. For example, whereas both areas of the bearing surfaces may be large when applied to distention of tubular passageways of large cross-sectional dimensions, in contrast both areas of the bearing surfaces will necessarily be relatively small when applied to the distention of tubular passageways of relatively small cross-sectional dimensions.

Regulation or control of the ratio of bearing surfaces given above is applicable to any combination of metals, amount of distention desired in each and the thicknesses of each, but become simplified with the equalization with the amount of distention desired and/or in the thicknesses of the metal component sheets. For example, if the amount of distention of a tubular passageway in a tube sheet is to be equal so that the distended tubular passageway will be bulged equally out of the faces of the tube sheet, the ratio of the bearing surface pressing against the softer sheet to the area of the bearing surface pressing against the harder sheet will then be equal to the ratio of the elastic limits of the harder sheet to the elastic limits of the softer sheet multiplied by the ratio of the thickness of the softer sheet to be distended to the ratio of the harder sheet to be distended. Where, in addition, the thicknesses of the component sheets to be distended are equal to the ratio of the area of the bearing surface pressing against the softer sheet to the area of the bearing surface pressing the harder sheet will be merely equal to the ratio of the elastic limits of the harder sheet to the elastic limits of the softer sheet. The term "elastic limits" is employed in this application in its accepted sense to define the maximum stress that a material will withstand without permanent deformation, and in practical sense is used interchangeably with the term "yield strength."

More specifically by reference to the drawings, in FIGURE 1, there is shown a tool 1 and an inflatable panel 2 formed from two superimposed component metal sheets 3 and 4, having different elastic limits. The adjacent areas of sheets 3 and 4 are selectively welded together in a pattern to provide a system of embryonic passageways 5 disposed between unjoined portions 6 and 7 and laterally defined between parts of the welded portion 8. Any combination of metals of different elastic limits

weldable to each other may be employed, for example, such as the different alloys of the same base metal which in the preferred embodiment may be exemplified in the pressure welding of 1100 type aluminum alloy to 3004 type aluminum alloy, both alloy designations in accordance with the Aluminum Association standards. For the above specific alloys, 1100 type aluminum alloy has an elastic limit or yield strength of 5,000 p.s.i. and the 3004 type aluminum alloy has an elastic limit or yield strength of 10,000 p.s.i.

10 In order to provide for the inflation of the system of embryonic passageways 5, a strip or unjoined portion 9 of panel 2, defining a corresponding embryonic tubular passageway, extends to the edge of the panel at 10 to provide a line of separation 11.

15 The tool or mandrel 1 is provided at the front end of a shank or shaft 11 with a working portion 12 having oppositely disposed complementary bearing surfaces 13 and 14 which will press against the unjoined portions, in inlet strip 9, of component sheets 3 and 4, respectively,

20 and distend the inlet strip or passageway 9 into the desired cross-sectional configuration so as to, for example, facilitate the attachment of any appropriate inflation nozzle. In order to facilitate the insertion of tool 1

25 into the passageway 9 the working portion 12 is provided with any conveniently shaped point 15 to initiate the initial separation of the unjoined portions. Attached to the rear portion of shank or shaft 11 is any conveniently shaped handle 16 which may be hand gripped for manual insertion of the mandrel within passageway 9.

30 To initiate the distention of panel 2, the point 15 of the tool 1 may be manually inserted into the laminated or unjoined strip 9 at the line of separation 11. If desired, the unjoined portion of the panel opposite this line of separation may be provided with an initial opening by

35 any conventional means, as for example, by the teachings of U.S. Patent No. 2,835,025 granted on May 20, 1958, to further facilitate the introduction of the distending tool into the unjoined strip 9. With the point 15 of the tool inserted in the unjoined strip 9, the tool is then manually forced further into the panel to a depth sufficient to

40 accomplish the distention desired. It is to be understood that although the tool has been described for manual operation, the tool may also and preferably, although not illustrated, take the form of a drift punch which may be driven into the unjoined strip 9 by any conventional vibrating tool.

45 As pointed out above, the working portion 12 may have any cross-sectional configuration desired corresponding to the desired distended configuration to be imparted in passageway 9. In the embodiment illustrated, the working portion 12 is provided with a configuration to impart a substantially circular cross-section in passageway 9. Accordingly, the front and lower part of the working portion

50 12 has a semi-cylindrical configuration merging into a rearwardly disposed portion in which the cross-sectional configuration is cylindrical. In effect, the lower half of the working portion 12 will form a semi-solid cylinder from which projects a semi-cylinder of shorter length to form the upper part of working portion 12, which together provide a circular distended configuration in passageway 9. Since in mandrels employed for providing circular configuration, the peripheries of the upper and lower parts will be substantially equal, the area of the bearing surface will be controlled and regulated by their length along tool 1. In the embodiment shown the shank or shaft 11 plays no part in the distention of passageway 9 and is preferably designed so as not to exert any force against the walls of passageway 9, and for convenience has been illustrated as of an elliptical configuration disposed in a horizontal plane.

55 In FIGURE 5 the working portion 12 of tool or mandrel 1 is shown partially inserted, as for example manually, within the embryonic passageway 9 of panel 2 wherein bearing surface 14 is pressed against the un-

60 70 75

joined portions of component sheet 4 opposite passageway 9 and bearing surface 13 presses against the unjoined portions of component sheet 3 opposite passageway 9. The amount of the areas of the bearing surfaces pressing against the respective unjoined portions on which they act will determine the areas of the unjoined portions on which the distending force will react to thereby regulate the distending pressures acting on the unjoined portions opposite their respective bearing surfaces. For example, with a tube sheet formed from a component sheet of 1100 type aluminum alloy pressure welded to a component sheet of 3004 type aluminum alloy, in which the unjoined portions are of substantially equal thickness so as to dispose the unjoined portions midway between the outer faces of the tube sheet, where equal distensions of complementary unjoined portions are desired, the ratio of the bearing surface to each other will be substantially equal to the inverse ratios of the yield strengths of the respective alloys on which they will act.

Specially, employing the elastic limits or yield strengths of the above aluminum alloys, the ratios of the bearing surface pressing or acting on the 1100 type aluminum alloy to the area of the bearing surface pressing on the 3004 type aluminum alloy will be substantially equal to the inverse ratio of the elastic limits of the respective alloys, that is

$$\frac{10,000 \text{ p.s.i.}}{5,000 \text{ p.s.i.}}$$

which is equal to a numerical ratio of 2. Accordingly, the area of the bearing surface on 1100 type aluminum alloy will be $\frac{1}{2}$ times the area of bearing surface acting on the 3004 type aluminum alloy. Where the embryonic passageway 9 of this specific panel has an initial width of 0.225 inch and is to be distended to a circular cross-sectional configuration having a diameter of 0.223 inch the area of the bearing surface acting on 1100 type alloy may be substantially 0.04375 square inch while the area of the bearing surface for distension of the 3004 type aluminum alloy may be 0.0875 square inch.

As indicated above, the invention is equally applicable to the sizing of partially or fully formed tubular passageways such as 18 in FIGURE 6. Passageway 18 is part of a distended system of passageways 19 formed between the pressure welded component sheets 20 and 21, for example as by the aforesaid U.S. Patent 2,690,002, which as discussed above, involves interposing a pattern of stop-weld between superposed metal component sheets, pressure welding and followed by inflation with distending pressure injected within the resultant pressure welded tube sheet. When the panel is fabricated, according to the process of the aforesaid patent, from metals having different elastic limits, the resultant blank or tube sheet upon inflation with fluid pressures, will be distended unequally in proportion to the elastic limits of the complementary portions defining the unjoined portions in the tube sheet. In sizing tubular passageway 18 of this embodiment, the complementary bearing surfaces of each working portion may be correlated so as to equalize the distension of the unjoined portions defining tubular passageway 18 whereby the walls of passageway 18 will be bulged equally out of opposite faces of the tube sheet. Such equalized distension of tubular passageway 18 facilitates the insertion of an appropriate connecting means from the tube sheet to other parts of a fluid system, for example, as in refrigerating systems.

In the specific embodiment shown, the distended tubular passageway 18 is sized so as to provide on different portions thereon progressively increasingly larger cross-sectional configurations. Such sizing is accomplished with a sizing tool 22 provided with a series of working portions 23, 24 and 25 disposed in spaced relationship to each other along the shaft or shank 26 of the tool. Each successive working portion, 23, 24 and 25, will have progressively greater cross-sectional configurations corre-

sponding to the cross-sectional configurations desired to be imparted in the tubular passageway 18. In each working portion the ratio of the bearing surface bearing on the softer metal to the area of the bearing surface acting on the harder metal will be determined as in the preceding embodiment.

To obtain the desired sizing of distended passageway 18, tool 22 is inserted into tube sheet 23 between the unjoined portions of the tube sheet defining the tubular passageway 18. The resultant sized tubular passageway 18 will have successive portions of progressively increased cross-sectional configurations. Thus, tubular passageway 18 will have a portion 27 having a cross-sectional configuration the same as the initial cross-sectional configuration of passageway 18, a portion 28 having an enlarged cross-sectional configuration imparted to it by working portion 23 of tool 22 and a portion 29 having a further increased cross-sectional configuration imparted to it by the working portion 24 of tube 22 and a portion 30 having a still further enlarged cross-sectional configuration.

Although the invention has been described in the preceding embodiment relative to embryonic or distended passages having initially uniform dimensions, it is equally applicable to the distention and sizing of passageways initially provided with a restriction, as for example by the process in U.S. Patent 2,822,151, granted on February 4, 1958. Such a configuration may be obtained by designing the pattern of weld-inhibiting material interposed between superposed component sheets so that a passageway narrows along its axis and then enlarges to its original dimensions. Upon pressure welding and expansion of the passageways between the sheets, the aforesaid passage will have portions 31 distended to a cross-sectional configuration corresponding to the initial dimensions of the stop-weld defining this portion and a constricted portion 32 corresponding to the narrowed portion of the stop-weld defining this portion of the passageway. As in the preceding embodiments, the fabrication of tube sheets initial expansion thereof with fluid pressure will cause unequal distension of the unjoined portions of the tube sheets in proportion to their elastic limits. A tubular passage 33 of this tube sheet containing tubular portions 31 and 32 may be further mechanically distended with a tool 34 so as to both equalize the distension and/or to adapt the tubular passage 33 for the reception of various connecting means. To accomplish this, sizing tool 34 is provided with two working portions, a working portion 35 for the sizing of constricted portion 32 and a working portion 36 for the sizing of tubular portion 31. As will be understood, the cross-sectional dimensions of the working portions and the ratio of the complementary bearing surfaces in each working portion will be correlated to each other as in the preceding embodiments. The resultant sized tubular passage 33 will have in the restricted tubular portion 32 a part 37 thereof corresponding to the initial dimension of constricted portion 32 and a sized part 38 thereof corresponding to the dimensions imparted to it by working portion 35 of sizing tool 34. In like manner, the tubular portion 31 of tubular passage 33 will have a part 39 thereof corresponding to the initial dimensions of tubular portion 31 and a part 40 having the cross-sectional dimensions imparted to it by working portion 36 of tool 34.

Although the invention has been described with reference to specific embodiments, materials and details, various modifications and changes, within the scope of this invention, will be apparent to one skilled in the art and are contemplated to be embraced within the invention.

70 What is claimed is:

1. The method of mechanically distending a tubular passageway of a metal tube sheet formed by selectively welding, in a pattern defining a system of passageways which comprises at least said passageway, areas of adjacent surfaces of superimposed sheets of metals having

different elastic limits wherein said welding defines said passageway between opposed unjoined portions of said sheets and laterally between welded portions of said sheets; said method comprising inserting between said unjoined portions a mandrel having a cross-sectional configuration corresponding to the desired distended cross-sectional configuration of said passageway said mandrel having and said insertion being made so as to apply a first bearing surface opposite and adjacent one of said unjoined portions having the lower elastic limit, and an oppositely disposed second bearing surface opposite and adjacent the other of said unjoined portions having the higher elastic limit wherein the ratio of the area of the bearing surface opposite and adjacent said one unjoined portion to the area of the bearing surface opposite and adjacent said other unjoined portion is equal to the ratio of said higher elastic limit to the said lower elastic limit times the ratio of the amount of distention desired in said one unjoined portion to the amount of distention desired in said other unjoined portion times ratio of the thickness of said one unjoined portion to the thickness of the other said unjoined portion.

2. The method of claim 1 wherein said sheets are of different alloys having the same base metal.

3. The method of claim 2 wherein said sheets are of different alloys of aluminum.

4. The method of claim 1 wherein the thicknesses of said unjoined portions are equal and wherein the ratio of the area of the bearing surface opposite and adjacent said one unjoined area to the area of the bearing surface opposite and adjacent said other unjoined portion is equal to the ratio of said higher elastic limit to said lower elastic limit times the ratio of the amount of distention desired in said one unjoined portion to the amount of distention desired in said other unjoined portion.

5. A method for mechanically distending tubular passageway of a metal tube sheet comprising selectively welding, in a pattern defining a system of embryonic passageways containing at least one embryonic passageway corresponding to said tubular passageway, areas of adjacent surfaces of superimposed sheets of different metals having different elastic limits whereby said welding defines said embryonic passageway between opposed unjoined portions of said sheets and laterally between welded portions of said sheets, inserting between said unjoined portions defining said embryonic passageway a mandrel having working portions thereon corresponding to the desired cross-sectional configuration of said tubular passageway, said working portion having and said insertion being made so as to apply a first bearing surface opposite and adjacent one of said unjoined portions having the lower elastic limit and oppositely disposed second bearing surface opposite and adjacent the other of said unjoined portions having the higher elastic limit wherein the ratio of the area of the bearing surface opposite and adjacent said one unjoined portion to the area of the bearing surface opposite and adjacent said other unjoined portion is equal to the ratio of said higher elastic limit to the said lower elastic limit times the ratio of the amount of distention desired in said other unjoined portion times the ratio of the thickness of said one unjoined portion to the thickness of the said other unjoined portion.

6. The method of claim 5 wherein said sheets are of different alloys having the same base metal.

7. The method of claim 6 wherein said sheets are of different alloys of aluminum.

8. The method of claim 5 wherein the thicknesses of said unjoined portions are equal and wherein the ratio of the area of the bearing surface opposite and adjacent said one unjoined area to the area of the bearing surface opposite and adjacent said other unjoined portion is equal to the ratio of said higher elastic limit to said lower elastic limit times the ratio of the amount of distention desired in

in said one unjoined portion to the amount of distention desired in said other unjoined portion.

9. The method of claim 8 wherein said sheets are of different alloys having the same base metal.

10. The method of claim 9 wherein said sheets are of different alloys of aluminum.

11. A method for mechanically distending tubular passageway of a metal tube sheet comprising selectively welding, in a pattern defining a system of embryonic passageways containing at least one embryonic passageway corresponding to said tubular passageway, areas of adjacent surfaces of superimposed sheets of different metals having different elastic limits whereby said welding defines said embryonic system of passageways between opposed

15 unjoined portions of said sheets and laterally between welded portions of said sheets, injecting along said system of embryonic passageways sufficient fluid pressure to permanently distend and bulge portions of said sheet opposite said passageways out of the faces of said sheets to form a corresponding system of passageways including said tubular passageway whereby the portions of said sheets having the lower elastic limit opposite said passageways are distended and bulges a greater amount than the portions of said sheets having the higher elastic limit opposite

20 said tubular passageway where the portions of said sheets having the lower elastic limit opposite said passageways are distended and bulges a greater amount than the portions of said sheets having the higher elastic limit opposite

25 said tubular passageway, sizing said passageway by inserting into said tubular passageway between the corresponding unjoined portions thereof a sizing mandrel corresponding to the desired sized cross-sectional configuration of said tubular passageway, said working portions

30 having and said insertion being made so as to apply a first bearing surface opposite and adjacent one of said unjoined portions of said tubular passageway having the lower elastic limit and an oppositely disposed second bearing surface opposite and adjacent the other of said unjoined portions of said tubular passageway having the higher elastic limit wherein the ratio of the area of the bearing surface opposite and adjacent said one unjoined portion to the area of the bearing surface opposite and adjacent said other unjoined portion is equal to the ratio of

35 said higher elastic limit to the said lower elastic limit times the ratio of the amount of distention desired in said one unjoined portion to the amount of distention desired in said other unjoined portion times ratio of the thickness of said one unjoined portion to the thickness of the other said

40 unjoined portion.

35 45 50 55 60 65 70 75 12. The method of claim 11 wherein said sheets are of different alloys having the same base metal;

13. The method of claim 12 wherein said sheets are of different alloys of aluminum.

14. The method of claim 11 wherein the thicknesses of said unjoined portions defining said tubular passageway are equal and wherein the ratio of the area of the bearing surface opposite and adjacent said one unjoined area to the area of the bearing surface opposite and adjacent said one

55 unjoined area to the area of the bearing surface opposite said other unjoined portion is equal to the ratio of said higher elastic limit to said lower elastic limit times the ratio of the amount of distention desired in said one unjoined portion to the amount of distention desired in said other separated portion.

15. The method of claim 14 wherein said sheets are of different alloys having the same base metal.

16. The method of claim 15 wherein said sheets are of different alloys of aluminum.

17. A mandrel for mechanically distending a tubular passageway of a metal tube sheet formed by selectively welding, in a pattern defining a system of passageways which comprises at least said passageway, areas of adjacent surfaces of superimposed sheets of different metals having different elastic limits wherein said welding defines said passageway between opposed unjoined portions of said sheets and laterally between portions of said sheets, said mandrel comprising a working portion having cross-sectional configuration corresponding to the desired distended cross-sectional configuration of said passageway,

said working portion having a first bearing surface for application opposite and adjacent one of said unjoined portions having the lower elastic limit and a complementary oppositely disposed second bearing surface for application opposite and adjacent the other of said unjoined portions having the higher elastic limit wherein the areas of both said bearing surfaces are unequal with the ratio of the area of the bearing surface opposite and adjacent said one unjoined portion to the area of the bearing surface opposite and adjacent said other unjoined portion equal to the ratio of said higher elastic limit to the said lower elastic limit times the ratio of the amount of distention desired in said one unjoined portion to the amount of distention desired in said other unjoined portion times

the ratio of the thickness of said one unjoined portion to the thickness of the other said unjoined portion.

18. The mandrel of claim 17 including a series of working portions in spaced relationship to each other with each successive portion having progressively greater cross-sectional configuration.
